UNITED STATES PATENT OFFICE

2,594,073

CONDENSATE DISPOSAL SYSTEM FOR
REFRIGERATORS

Carl G. Robbins, Chicago, Ill.

Application August 6, 1948, Serial No. 42,933

8 Claims. (Cl. 62—116)

1

This invention relates to improvements in refrigerators, and more particularly to improvements in means for the disposal of condensate in refrigerators of the so-called two-temperature type.

At the present time, certain types of refrigerators are provided which have two refrigeration compartments. One of these is held at a low temperature, considerably below freezing, and the other is held at a higher temperature, usually sufficiently low to prevent spoilage and yet high enough to prevent freezing. In the preferred form of construction, the higher temperature compartment is cooled by coils which are placed in contact with the liner wall, rather than being exposed to the air inside the refrigerator. This prevents the coils from frosting and causes a more even withdrawal of heat through the liner wall.

Because the wall is cool, however, moisture condenses on the wall and eventually runs down the sides and is accumulated in a container. After a period of time, this container must be emptied. Although this is not a very complicated chore, it is one which is often neglected with the result that the water runs out of the container and wets the floor. This may cause considerable damage as well as make a mess which is undesirable.

If the container is inside the refrigerator, it uses up valuable storage space. If it is outside the cabinet, it still further complicates the manner of its storage and/or emptying.

By my present invention, I have provided a disposal system which automatically disposes of all the condensate and which never requires any attention except under unusual conditions. The manner of disposal of condensate also assists in cooling the refrigerant after it is compressed, thus increasing the efficiency of its operation. The system is carried out by the addition of a few simple parts which are readily accessible for cleaning and extremely easy to remove.

Although the invention about to be described is extremely useful in connection with the so-called two-temperature or moist cold compartment type of refrigerator, it will be found that it can be used to advantage with the conventional type of refrigerator where the evaporator is disposed inside of the box and where periodical defrosting must be carried out, if greatest efficiency is realized. Particularly is it useful with refrigerators that have an automatic defrosting cycle.

Still other advantages of the invention and the invention itself will become more apparent from

2

the following description of an embodiment thereof, which description is illustrated by the accompanying drawings and forms a part of the specification.

5 In the drawings:

Fig. 1 is a side elevational view of a complete refrigerator with the bottom portion broken away and shown in section to more clearly illustrate the invention;

10 Fig. 2 is an enlarged fragmentary elevational view illustrating my invention;

Fig. 3 is a plan view thereof;

Fig. 4 is a front elevational view thereof;

15 Fig. 5 is an enlarged detail view partly in section and partly in elevation, showing one form of drain pipe;

Fig. 6 is a view similar to Fig. 1 illustrating the invention applied to a different style of refrigerator cabinet;

20 Fig. 7 is a perspective view of the tray used in the application shown in Fig. 6;

Fig. 8 is an enlarged detail view of the application of my invention shown in Fig. 6.

Referring now to the drawings, throughout 25 which like parts are designated by like reference characters, and particularly to Fig. 1, there is illustrated a refrigerator which includes the cabinet having an outer shell 10 and an inner liner 11 which is spaced from the outer shell and insulated therefrom by insulation 13. A door 14 is provided for closing the front opening and likewise is insulated.

The particular refrigerator shown is illustrated more in detail in the copending application of 30 Evans T. Morton for "Refrigerator," Ser. No. 720,080, filed January 3, 1947. As shown in that application, the lower compartment is cooled by the coils which are in intimate engagement with the exterior of the liner 11.

40 The base of the cabinet is provided with a machinery compartment 15, and a motor compressor unit 16 is disposed in the compartment being supported by brackets such as 17 on a sub-frame 18. Below the sub-frame 18 is provided the base 20 which has feet 21 upon which the cabinet rests.

45 The evaporation coils, not shown, but which are clearly illustrated in the aforesaid case are connected to the compressor through the low pressure tube 23. The refrigerant is compressed in the compressor and then passes from the compressor through the high pressure conduit 25 to the condenser 26. From the condenser 26 connection is made to the evaporator tubes by the line 27.

As is well known to those versed in the art, the refrigerant is compressed in the compressor, and it is necessary to cool it before it is fed to the evaporator coils. Therefore, the refrigerant in the line 25 causes that line to be at a high temperature. As shown in Fig. 1, the back of the refrigerator is provided with a duct 30 which assists in providing air circulation through the condenser 26, this duct being open at the top and the bottom so that a draft may be realized there-through.

As previously stated, the condensate collects on the liner 11 and gradually runs down the walls to the bottom of the compartment. The condensation of moisture is not wholly undesirable because the amount of moisture removed is small as compared with a refrigerator where the evaporator coils are directly exposed to the inside air of the cabinet, and the moist cold assists in maintaining the food, especially garden vegetables, in a fresh and crisp condition. The bottom wall of the liner slants toward the center line of the refrigerator and also slants from the back toward the front as indicated at 31. At its lowest spot an outlet for the condensate is provided which extends completely through the liner, the insulation and the outer cabinet and into the machinery compartment. In other words, the bottom of the inner liner is so shaped that the condensate runs to one spot and a drain is provided at the lowest spot, through which the condensate may run, into the machinery compartment.

As shown in Fig. 5, the wall 31 drains to a lower portion 32 that is provided with an opening 33. A rubber coupling is provided for the opening and has an upper flange 34 provided with a tapered edge portion 35 for intimate contact with the liner. A peripheral groove 36 is provided into which the edge of the liner, which defines the opening 33, extends in intimate engagement. The coupling is provided with a bore 38 extending through it, and a tube 39 is disposed in the bore, the tube having an enlarged portion 40 that engages with a circular boss 41 on the inside of the bore 38. The end 42 of the coupling is of reduced diameter, the entire assembly providing a close fluid-tight fit. Above the boss 41 in the coupling and around the enlarged end 40 of the tube is an annular channel 44. A cap is provided having a curved upper surface 45 and provided with a skirt 46 whereby the cap is supported in the channel 44 spaced slightly above the surrounding parts. Apertures 47 are provided in the lower end of the skirt 46 which is held in spaced relation to the tube 40 by lugs 48. Water seeping into the portion 32 may escape through the aperture 47 and then upward over the tube 40, the combination acting as a trap. The tube then extends down through the lower liner and is supported by a grommet 50 disposed in the outer liner 10.

The tube 25, on the high pressure side of the compressor unit, instead of extending directly to the condenser, as is common practice, in this instance is carried to the top of the machinery compartment and secured to the bottom wall of the refrigerator by a clip 55. It then extends forward and is inclined downward as indicated at 56. It then extends laterally as shown at 57, Fig. 3, and then is bent back upon itself as indicated at 58 to provide a loop. The convolutions of the loop lie in substantially the same plane as the part 56 which slants from the roof of the machinery compartment downward to the front

of the cabinet. This loop is supported in position by a clip 80 secured to a bracket 86 on the bottom wall of the cabinet at 81, and is provided with a pair of downwardly extending parts 82 having hook shaped portions 83 on their respective ends into which the parts 57-58 of the loop may be engaged. As can best be seen in Fig. 3, there are two of these hooks disposed to engage the loop 57-58 at the center portion. It will be appreciated, however, that one such support may be sufficient, and that the number and placement thereof may be varied. The run 58 then bends back parallel to the tube 56 as indicated at 59 being held by the same clip 55 to the top of the machinery compartment. The tube 59 then connects directly to the top of the condenser 26.

The tube 39 drains into a receptacle which is removably disposed beneath it. This receptacle is so designed that the condensate runs to the lower part in which the loop 57-58 is disposed so that the liquid is in contact with the hot loop. It is so supported that when it is removed, the act of removal results in a lowering of the receptacle so that it clears the loop 57-58 when it is withdrawn or raises it when it is inserted in the machinery compartment.

The receptacle is preferably made of transparent plastic which is deep in the front and is shallow at the back. It comprises a bottom wall 60 which slants upward from the front to the back, being provided with triangular side walls 61 and a vertically extending front wall 62. The front wall is provided with a recess 63 having a forward and downwardly extending lip 64 to provide a convenient handle hold. As can best be seen in Fig. 2, the plane of the bottom wall is substantially parallel to the plane of the portions 56, 57, 58 and 59 of the heated tube, and when the receptacle is in position, the loop 57-58 is disposed spaced from but close to the bottom and forward part of the receptacle.

Brackets are used for supporting the receptacle and providing guide rails for guiding the receptacle upon insertion and removal. There may be two such brackets disposed for engagement with the sides and the portions of the bottom wall adjacent the sides. These each include a flat top portion 70 which may be secured to the top wall of the machinery compartment and are provided with downwardly extending portions 71 which carry, at their ends, the inwardly extending rails 72. These rails, likewise, provide a surface which slants downward toward the front of the cabinets and extend inward toward each other to provide ample support for the receptacle.

Each of the rails is provided with a rectangular opening 74 into which lugs on the bottom adjacent the opposite ends of the receptacle may extend. The lugs are provided with a front wall 76 substantially perpendicular to the bottom thereof and a slanting wall 77 which slants upward and merges with the bottom of the receptacle.

In the case of the cabinet shown in Fig. 1 the front of the machinery compartment is closed by a bin for holding dry vegetables or the like. This bin is best shown in Fig. 1 and includes the exterior finish cover 90 which is designed to match the door 14 and to provide a smooth exterior finish for the front of the refrigerator. The cover 90 carries the bin proper 91 which extends into the machinery compartment. The entire assembly is preferably hinged at 92 to the bottom of the cabinet. Since any type of closure may be provided for this portion of the refrigerator no

further description will be made. Suffice to say that the front portion may be pulled forward; in this instance, tipping about its bottom part at the hinge 92 to allow free access to the front of the cabinet below the door 14 and thence the water receptacle which then appears as shown in Fig. 4.

When it is desired to remove the receptacle, the front end is raised by engaging the hand hold 63—64, to disengage the lugs 75 from the openings 74 in the rails. The receptacle is then pulled forward and allowed to slide down the rails 72. This causes the receptacle to be lowered, as it is withdrawn thus allowing the same to easily clear the tubing 56—59.

When it is desired to replace the receptacle, it is merely placed with the rear portion in engagement with the rails and pushed backward. This causes it to rise into position around the tubing. It is pushed backward until the lugs 75 drop into the openings 74 at which time it is in position.

In operation, the condensate from the walls inside the refrigerator drains, as described, into the receptacle where it runs to the front and comes into contact with the tubing. The tubing, being hot, or warm, causes the liquid to evaporate, the vapor escaping to the room. Because the condensate escapes so quickly to the receptacle, there is not sufficient time for it to collect but a small amount of food odors and there is no noticeable undesirable odor due to the vaporization.

Besides disposing of the moisture, the act of disposal thereof actually increases the efficiency of the unit due to the heat transfer from the tubing to the water and the resultant cooling due to vaporization.

In Fig. 6, I have shown my invention applied to another form of refrigeration cabinet. The main difference in this case is that due to the fact that smaller more compact compressor units are available, the interior of the refrigerator is extended for the full length of the cabinet. In this instance, the door 14a extends from the top to the bottom of the cabinet and the bottom of the cabinet is closely adjacent to the floor. The compressor unit 16 is housed at the rear of the cabinet and the condenser unit 26 is raised in the stack or flue 30.

The condensate as before collects on the walls of the refrigerating compartment and gathers in the depressed portion of the bottom of the compartment from where it drains through the tube 39 into the receptacle. In this embodiment, the bottom of the receptacle is horizontal to provide for larger capacity in the receptacle which must necessarily be made less deep than in the embodiment previously described. The side walls are shaped of two right-triangular or trapezoidal walls. The upper triangular side walls 93 the long sides of which form the upper rim of the receptacle are spaced somewhat wider apart than the lower triangular parts 94 so that the portions of the side walls joining their hypotenuses forms an inclined plane 95. These inclined planes which are on opposite sides of the receptacle engage with the sloping guide rails 97 in the lower portion of the refrigerator and thereby support the receptacle in position. The guide rails are carried by brackets similar to those described in the previous embodiment which are fastened to the lower wall of the refrigerator in the same manner. Rectangular openings 14 in the guide rails and lugs 75 on the inclined planes are provided similarly as before to hold the receptacle in position. The position and shape of the receptacle is such that upon opening the door 14a, the re-

ceptacle can be pulled out, sliding down its guide rails and onto the floor with sufficient clearance to avoid the tubes.

Having thus described my invention, I am aware that extensive departures may be made from the form without deviating from the spirit or scope of my invention.

I claim:

1. A condensate disposal system for a refrigerator including a cabinet and a refrigerant compressor, a condenser and an evaporator with refrigerant conduits connecting them, said conduit between the condenser and the compressor being disposed beneath the bottom wall of the cabinet and being formed with a portion extending downwardly in spaced relation thereto, a drain for said cabinet, and a receptacle disposed opposite said drain and means for supporting said receptacle with said downwardly extending portion of the conduit adjacent the bottom thereof, said supporting means being formed to provide guides for lowering and raising said receptacle from around said conduit upon removal or replacement of the receptacle, the fluid in the receptacle being in heat transfer relation with the conduit when the receptacle is in position.

2. A condensate disposal system for a refrigerator including a cabinet and a refrigerant compressor, a condenser and an evaporator with refrigerant conduits connecting them, said conduit between the condenser and the compressor being disposed along the bottom wall of the cabinet and being formed with a portion extending downwardly in spaced relation thereto, a drain for said cabinet, and a receptacle disposed opposite said drain and means for supporting said receptacle with said downwardly extending portion of the conduit adjacent the bottom thereof, said supporting means being formed to provide guides for lowering and raising said receptacle from around said conduit upon removal or replacement of the receptacle, the fluid in the receptacle being in heat transfer relation with the conduit when the receptacle is in position, and interlocking means on the guide means and receptacle to hold the same in position.

3. A condensate disposal system for a refrigerator including a cabinet and a refrigerant compressor, a condenser and an evaporator with refrigerant conduits connecting them, said conduit between the condenser and the compressor being disposed along the bottom wall of the cabinet and being formed with a portion extending downwardly in spaced relation thereto, a drain for said cabinet, and a receptacle disposed opposite said drain and means for supporting said receptacle with said downwardly extending portion of the conduit adjacent the bottom thereof, said supporting means being formed to provide guides for lowering and raising said receptacle from around said conduit upon removal or replacement of the receptacle, the fluid in the receptacle being in heat transfer relation with the conduit when the receptacle is in position, said receptacle having a front wall at the front of the refrigerator formed to provide a hand hold for removing and inserting it.

4. A condensate disposal system for a refrigerator including a cabinet and a refrigerant compressor, a condenser and an evaporator with refrigerant conduits connecting them, said conduit between the condenser and the compressor being disposed along the bottom wall of the cabinet and being formed with a portion extending downwardly in spaced relation thereto, a drain

for said cabinet, and a receptacle disposed opposite said drain and means for supporting said receptacle with said downwardly extending portion of the conduit adjacent the bottom thereof, said supporting means being formed to provide guides for lowering and raising said receptacle from around said conduit upon removal or replacement of the receptacle, the fluid in the receptacle being in heat transfer relation with the conduit when the receptacle is in position, said receptacle having a front wall at the front of the refrigerator formed to provide a hand hold for removing and inserting it, a door for the front of the cabinet for closing the cabinet and concealing the receptacle.

5. In combination with a refrigerator having a compressor and a condenser and a conduit extending from the compressor to the condenser, a drain pipe in the bottom of the refrigerator adapted to receive condensate from the walls thereof, a tray disposed below the drain pipe to receive the condensate, said conduit being formed to extend toward the tray, said conduit being provided with laterally extending convolutions disposed in the tray, a pair of guide rail supports having guide rails for supporting the tray, said guide rails slanting downward toward the front of the refrigerator, said tray being supported by the guide rails, said guide rails formed to guide said tray upon removal to effect the lowering of the tray away from said conduit.

6. In combination with a refrigerator having a compressor and a condenser and a conduit extending from the compressor to the condenser, a drain pipe in the bottom of the refrigerator adapted to receive condensate from the walls thereof, a tray disposed below the drain pipe to receive the condensate, said conduit being formed to extend toward the tray, said conduit being provided with laterally extending convolutions disposed in the tray, a pair of guide rail supports having guide rails for supporting the tray, said guide rails slanting downward toward the front of the refrigerator, said tray being supported by the guide rails, said guide rails formed to guide said tray upon removal to effect the lowering of the tray away from said conduit, means on the guide rails and tray for locking the tray in the guide rails.

7. In combination with a refrigerator having a compressor and a condenser and a conduit connecting the compressor to the condenser, a drain in the bottom of the refrigerator adapted to receive condensate from the walls thereof, a tray

disposed below the drain to receive the condensate, said conduit being formed to extend into the tray and into the condensate to evaporate the condensate, said conduit being disposed adjacent the floor of the refrigerator spaced from the front and extending downward toward the front and provided with laterally extending convolutions at the front, a pair of guide rail supports having guide rails for supporting the tray, said guide rails slanting downward toward the front of the refrigerator, said tray being deeper toward the front than the back with the bottom wall slanting upward and disposed for engagement with the guide rails, said guide rails formed to provide guide means to guide said tray upon removal to effect lowering of the tray away from said conduit, means on the guide rails and tray for locking the tray in the guide rails.

8. In combination with a refrigerator having a compressor and a condenser and a conduit extending from the compressor to the condenser, a drain in the bottom of the refrigerator adapted to receive condensate from the walls thereof, a tray disposed below the drain to receive the condensate, a pair of guide rail supports having guide rails for supporting the tray, said guide rails slanting downward toward the front of the refrigerator, said tray being deeper toward the front than the back with the bottom wall slanting upward and disposed for engagement with the guide rails, said conduit being secured to the bottom of the refrigerator spaced from the front and extending downward spaced from the bottom toward the front and provided with laterally extending convolutions at the front, said guide rails formed to guide said tray upon removal to effect lowering of the tray away from said conduit, said guide rails being formed with openings therein and lugs on said tray for interlocking engagement with said rails at said opening.
